CLAIM

I claim the ornamental design for a dispenser cap, as shown.

DESCRIPTION

FIG. 1 is a perspective view of the dispenser cap incorporating the ornamental design;

FIG. 2 is a perspective view thereof;

FIG. 3 is a front view thereof;

FIG. 4 is a side view thereof; the opposite side being a mirror image;

FIG. 5 is a top view thereof;

FIG. 6 is a back view thereof; and,

FIG. 7 is a bottom view thereof.

The broken lines are included for environmental purposes only and form no part of the claimed design.
